Patented Feb. 3, 1976

238,668

COMBINED THERMOMETER, SCALE AND PERPETUAL CALENDAR

Arthur T. Michaud, 9255 Doheny Road,
Los Angeles, Calif. 90069

Filed May 15, 1974, Ser. No. 470,112

Term of patent 14 years

Int. Cl. D19—03

U.S. Cl. D19—21

Fig. 1.

Fig. 2.

Fig. 3.

Fig. 4.

FIG. 1 is a perspective view of a combined thermometer, scale and perpetual calendar showing my new design;

FIG. 2 is a left end elevational view;

FIG. 3 is a rear elevational view;

FIG. 4 is a bottom plan view.

The number 78 on the center strip in FIG. 1 is shown only as typical of the temperature indicator. The partially disclosed scales are understood to be continuous between the portions shown.

I claim:

The ornamental design for a combined thermometer, scale and perpetual calendar, as shown and described.
